ICE CREEPER

Clarence Harvey, Canastota, N. Y.

Application December 4, 1942, Serial No. 467,885

5 Claims. (Cl. 36—61)

This invention relates to ice creepers designed primarily for use with shoes or boots, the construction of the ice creeper being such that it may be readily and easily positioned over the heel of the boot or shoe, and securely held in place, without the use of screws, cement or similar securing means.

An important object of the invention is to provide an ice creeper including a wide elastic supporting member adapted to fit around the heel of the shoe or boot to which the creeper is applied, the elasticity of the supporting member being such as to securely grip the heel and prevent displacement or movement of the creeper with respect to the heel.

A further object of the invention is to provide an ice creeper which may be readily and easily moved from its inactive position within the instep portion of the shoe, to its active position, directly over the bottom of the heel.

Still another object of the invention is to construct the spur plate of the creeper to fit the lower lift of the heel, to insure against movement of the spur plate with respect to the heel when in use.

A still further object of the invention is to provide an ice creeper which may be used at the ball of the foot.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a side elevational view illustrating an ice creeper constructed in accordance with the invention, as positioned on the heel of a shoe.

Figure 2 is a bottom plan view thereof.

Figure 3 is a sectional view taken on line 3—3 of Figure 1.

Figure 4 is a sectional view taken on line 4—4 of Figure 1.

Referring to the drawing in detail, the ice creeper embodies a wide elastic supporting band indicated by the reference character 5, the band being of a size, so that when it is stretched over the heel of a shoe or boot, the band will securely grip the heel.

Vulcanized to the rear portion of the band 5, 55

is an elastic strip 6, the strip 6 providing the attaching means between the spur plate 7 and the band 5.

The spur plate 7 is of a shape to fit the bottom or lower lift of the standard heel, and is provided with upwardly extended tongues 8 formed adjacent to the edge of the plate at the sides of and rear thereof, which tongues engage the lower lift of the heel to prevent lateral movement of the spur plate with respect to the heel.

Formed integral with the plate, and disposed adjacent to the front edge thereof, are upwardly extended flanges 9 that are formed with elongated openings that accommodate the strip 6, 15 whereby the band is securely held on the plate.

Spurs indicated at 10 are punched from the spur plate 7, and are arranged in a row across the front portion of the plate, the spurs 11 which are also punched from the plate being disposed 20 adjacent to the side edges of the plate, and arranged on a line drawn through the center of the plate, transversely of the plate.

From the foregoing it will be seen that due to the construction shown and described, the spur plate 7 will, due to the elasticity of the strip 6, be held into close engagement with either the lowermost lift of the shoe, or in a position as shown in dotted lines in Figure 1 of the drawing, where the plate is out of the way, but ready for immediate use, by merely stretching the strip 6 and moving the spur plate to the position as shown in full lines.

It might be further stated, that because of the construction of the supporting band, the ice creeper may be secured in position on shoe heels of practically any size and shape, the elasticity of the band permitting the band to conform to the shape of the heel, thereby eliminating the necessity of using screws or similar fastening means 40 which not only disfigure the shoe heel, but frequently become loose and render the creeper inoperative to accomplish its purpose.

What is claimed is:

1. An ice creeper for shoe heels, comprising a wide elastic band adapted to be stretched over a shoe heel, an elastic strip secured to said elastic band, a spur plate to which the elastic strip is secured, ears extending upwardly from the edges of the plate and adapted to engage the edges of the heel on which the creeper is positioned, restricting movement of the plate with respect to the heel, and said elastic strip adapted to hold the plate within the instep of the shoe or against the bottom of the heel of the shoe.
2. An ice creeper for shoe heels, comprising a

wide elastic band adapted to be stretched over a shoe heel, an elastic strip secured to said elastic band, a spur plate to which the elastic strip is secured, said elastic strip adapted to draw the spur plate into engagement with either the forward edge of the heel, or against the bottom of the heel, securing the spur plate in position on the heel.

3. An ice creeper for shoe heels, comprising a wide elastic band adapted to be stretched over a shoe heel, an elastic strip secured at a point intermediate its ends, to the rear portion of the elastic band, a spur plate to which the ends of the elastic strip are secured, means on the spur plate for engaging the edges of a shoe heel preventing movement of the spur plate with respect to the heel, and said elastic strip adapted to draw the plate into engagement with either the front surface of the heel, or the bottom of the heel.

4. An ice creeper for shoe heels, comprising a yieldable member adapted to embrace the heel of a shoe, a yieldable strip secured to the yieldable member, at the rear of the yieldable member,

the ends of the yieldable strip extending forwardly, a spur plate to which the yieldable strip is secured, ears extending from the spur plate and adapted to engage the heel on which the creeper is positioned, holding the spur plate against lateral movement, and said yieldable strip adapted to hold the spur plate into engagement with either the front surface of the heel, or the bottom of the heel.

5. An ice creeper for shoe heels, comprising a yieldable band adapted to embrace the heel of a shoe, a yieldable strip secured to the yieldable band at the rear thereof, the ends of the yieldable strip extending forwardly, a spur plate adapted to fit over the bottom of a heel, said yieldable strip being secured to the spur plate adjacent to the front edge thereof, and said yieldable strip adapted to draw the plate into engagement with either the front edge of the heel when the plate is inactive, or against the bottom of the heel when the plate is positioned for use.

CLARENCE HARVEY.
